UNITED STATES PATENT OFFICE

112,465

DESIGN FOR A ROTARY WELL DRILLING UNIT

August R. Maier, Dallas, Tex.

Application October 18, 1938, Serial No. 80,536

Term of patent 14 years

To all whom it may concern:

Be it known that I, August R. Maier, a citizen of the United States and a resident of Dallas, county of Dallas, and State of Texas, have invented a new, original, and ornamental Design for a Rotary Well Drilling Unit, of which the following is a specification, reference being had to the accompanying drawings, forming a part thereof.

Fig. 1 is a front perspective view of the rotary

well drilling unit showing my new design; Fig. 2 is another front perspective view looking in the direction opposite from that of Fig. 1; Fig. 3 is a front elevation view; and Fig. 4 is a top plan view thereof.

I claim:—

The ornamental design for a rotary well drilling unit, as shown.

AUGUST R. MAIER.
